UNITED STATES PATENT OFFICE.

DAVID S. JACOBUS, OF JERSEY CITY, NEW JERSEY, ASSIGNOR, BY MESNE ASSIGNMENTS, TO FULLER LEHIGH COMPANY, A CORPORATION OF DELAWARE.

FURNACE WALL.

Application filed July 9, 1925. Serial No. 42,367.

My present invention relates to furnace wall constructions, particularly furnace walls in which the walls are subjected to considerable variation in heat conditions, so that the several parts should be movable relatively to each other, and more particularly walls adapted for use in air-cooling furnaces.

My invention will be best understood from the following description and the annexed drawings, in which Fig. 1 is a vertical longitudinal section of a steam boiler furnace embodying my invention; Fig. 2 is an enlargement of a portion of the rear wall of Fig. 1; Fig. 3 is a section on the line 3—3 of Fig. 2, and Fig. 4 is a modification of the arrangement shown in Fig. 3.

Like reference characters indicate like parts in the different views.

In the illustrative embodiment, the furnace chamber 10 is provided with vertically disposed walls to form a chamber substantially rectangular in cross-section, the front wall 11 having a combustion air passage 12 communicating through the openings 13 with the combustion chamber. Beneath the furnace floor 14 is a passage 15, receiving air from a duct 16 heated by an air heater 17, the air for the air heater being forced into the air heater by the fan 18. Above the furnace chamber is a water tube steam boiler of a known form, the waste gases from which pass through the flue 19 to the air heater 17, and from thence to the smoke outlet 20. In the furnace roof 21 is one or more powdered fuel burners 22 supplied by air from a cross duct 23 connected by a duct 24 to the upper part of the air heater 17, the air for the duct 24 being taken from the lower part of the air heater through the fan 25. Air from duct 16 is also supplied to ducts 28 in the rear wall, from whence it flows, in the illustrative arrangement, through horizontal ducts in the side walls 45 into passage 12 and so into the furnace chamber through openings 13. The specific arrangement of the air supply for the furnace is no part of my present invention and further description thereof will be unnecessary. This arrangement, however, is more particularly described in my copending application Serial No. 37,641, filed June 17, 1925. The rear and side furnace walls, in the illustrative embodiment, are of the same construction and a description of one

of them will, therefore, suffice for all of them.

As shown in Fig. 1, the rear wall is made up of a plurality of sections, each substantially vertical, but with the successive higher sections stepped rearwardly, so that the total effect of the several sections is an outwardly inclined wall. Each of the sections is independently supported by fixed members extending beneath the sections, and since all of the sections are substantially alike, a description of one of them will be sufficient.

In Fig. 2, I have indicated an inner wall 26, the outer portion of the wall 27 being spaced from the inner wall 26 to form an air passage 28, the inner and the outer parts of the wall being held in spaced relation in any suitable manner, as by the dividing tile 29.

Beneath the sections extends a pair of fixed I-beams 30 to carry the weight of the wall, a metallic plate 31 resting on the I-beams and supporting both parts 26, 27 of the wall. The ends of these beams are connected to the usual steel frame work supporting the boiler and its setting. The inner part 26 of the wall is carried up alongside of the next higher section 26' so as to make a sliding joint between 26 and 26'. In order to maintain the parts 26 and 26' together, I provide one or more courses of special tile 32 in the part 26 and special tile 33 in the part 26', these parts being arranged as shown best in Fig. 3, with interlocking tongue portions. It will be noted that, in the illustrative embodiment, each tile 32 is equal in height to one course of the regular tile in the wall and tile 33 equal to two courses. When the wall 26 moves vertically, the tile 32 will slide over the tile 33 and, at the same time, the interlocking hooks on the two sets of tile will keep the parts of the wall 26 and 26' together. A suitable casing 34 may be provided on the exterior of each section.

The overlapping of the parts 26 and 26' insures complete protection for the metal parts which support the several sections and, at the same time, permit the sections to move relatively to each other as the wall is subjected to varying heat conditions. Such movement may arise from expansion of the tiling of the wall or the springing of the supporting metal work under the sections. By providing a possible relative ver-

100

105

110

tical movement between special tile 32 and 33 equal to the thickness of one of the courses of regular tile in the wall, any possible inaccuracy in the vertical spacing of the supports for the several sections or their not being on the same level throughout their length will not affect the laying up of the wall nor necessitate the cutting of any of the regular tile to produce a thin course.

10 The possible difference in expansion between the inner and outer parts of a section will be so small because of the short vertical height of each section, that the tile 29 connecting these parts will not be affected, 15 which would not be the case if the entire height of the wall were in a single section instead of a number of short sections. With the wall all in one piece, the relative motion at the upper part of the wall between the inner and outer parts might be sufficient to 20 rupture tile 29 or incline them at an angle to the horizontal. By dividing the wall into short sections, as shown, the use of the tile 29 connecting the inner and outer parts 25 is made possible.

It will be understood that the arrangement which I have shown is merely illustrative and that the embodiment of my invention may be widely varied.

30 The arrangement of Fig. 4 is similar to that of Fig. 3, except that fewer of the special tile 32 are used and more of the ordinary brick used in building such walls.

I claim:—

35 1. A furnace chamber having a wall there-of made up of a plurality of sections ar-ranged in stepped relation, each section com-prising an inner and an outer wall spaced apart to form an air duct therebetween, a 40 fixed support beneath each section to support both said inner and said outer walls thereof, the inner wall of each section being extended upward into overlapping sliding engagement with the lower part of the inner face of the 45 next higher section.

2. A furnace chamber having a wall there-of made up of a plurality of sections ar-ranged in stepped relation, each section com-prising an inner and an outer wall spaced apart to form an air duct therebetween, a 50 metallic plate extending beneath both said inner and said outer walls, a fixed support beneath said plate the inner wall of each section being extended upward into overlapping sliding engagement with the lower part of the inner face of the next higher section, and the outer wall of each section terminat-ing below the fixed support of the next 55 higher section.

60 3. A furnace chamber having horizontally disposed cooling air passages in a wall there-

of, said wall having a plurality of sections, each section having a beam beneath the same and double walls above the beam to form the air passage, the top of an air pas-sage in one section being spaced from the beam of the next higher section and the inner face of one section being extended upward in front of the beam of the next higher section into overlapping sliding engagement with 70 the lower part of the inner face of the next higher section.

4. A furnace chamber having a wall there-of made up of a plurality of sections ar-ranged in stepped relation, each section com-prising an inner and an outer wall spaced apart to form an air duct therebetween, a 75 fixed support beneath each section to support both said inner and said outer walls thereof, the inner wall of each section being extended 80 upward into overlapping sliding engagement with the lower part of the inner face of the next higher section, and tile in said over-lapping parts having interengaging portions to hold said overlapping portions against 85 relative horizontal motion and to permit relative vertical motion therebetween.

5. A furnace chamber having a wall there-of made up of a plurality of sections ar-ranged in stepped relation, each section com-prising an inner and an outer wall spaced apart to form an air duct therebetween, a 90 fixed support beneath each section to support both said inner and said outer walls thereof, the inner wall of each section being extended 95 upward into overlapping sliding engagement with the lower part of the inner face of the next higher section, one of said overlapping parts having tile therein with a relatively thin portion extending into the other of said 100 overlapping parts and having a hook engag-ing with a relatively thick tile in said other overlapping part, whereby said overlapping parts are free to move relatively vertically and are locked against relative horizontal 105 motion.

6. A furnace chamber having a wall there-of made up of a plurality of sections ar-ranged in stepped relation, each section com-prising an inner and an outer wall spaced 110 apart to form an air duct therebetween, a fixed support beneath each section to sup-port both said inner and said outer walls thereof, the inner wall of each section being extended upward into overlapping sliding 115 engagement with the lower part of the inner face of the next higher section, and means to hold said overlapping portions against relative horizontal motion and to permit relative vertical motion therebetween.
